GEARING FOR SKATES

Samuel Segal, Brooklyn, N. Y.

Application August 22, 1935, Serial No. 37,297

23 Claims. (Cl. 74—307)

The subject matter of the present invention is concerned with a skate and more particularly is directed to a functionally and structurally improved roller skate which will stand up under considerable usage and rough handling, which may be conveniently and readily assembled, and which when disorganized or out of adjustment may be readily repaired or readjusted by the removal and replacement of relatively few inexpensive parts.

The invention accordingly comprises the features of construction, combination of elements, arrangement of parts which will be exemplified in the construction hereinafter set forth and the scope of the application thereof will be indicated in the appended claims.

The present invention will be best understood from the following discussion of several typical structural embodiments, reference being had to the accompanying drawings in which:

Fig. 1 is a longitudinal elevational view of the skate according to my invention, partly illustrated in section.

Fig. 2 is a bottom view of the skate illustrated in Fig. 1.

Fig. 2A is a section taken on the line 2A—2A of Fig. 1.

Fig. 3 is a transverse section on the line 3—3 of Fig. 1.

Fig. 3A is a fragmentary view showing a folded position of the key relative to its bolt.

Fig. 4 is a section on the line 4—4 of Fig. 1.

Fig. 4A is an elevational view of a wheel and its shaft.

Fig. 5 is a fragmentary section on the line 5—5 of Fig. 2.

Fig. 5A is a fragmentary view along the line 5A—5A of Fig. 1 showing the clutch in section.

Fig. 6 is a section on the line 6—6 of Fig. 1.

Fig. 6A is a section on the line 6A—6A of Fig. 6.

Fig. 7 is a side elevational fragmentary view of a slightly modified clamping jaw.

Fig. 7A is a longitudinal view of a wheel shaft.

Fig. 8 is a fragmentary view of Fig. 1.

Fig. 9 is an enlarged sectional view of a wheel including an odometer device according to the invention.

Fig. 10 is a front elevational and broken view of the wheel illustrated in Fig. 9 and

Fig. 11 is an exploded or disassembled view of the parts of the odometer.

Illustrative of the embodiments disclosed in the several views of the drawings, the skate according to my invention is generally designated 10 and comprises complementary slidable front

and rear shoe supporting plate sections 11 and 12 to each of which is appropriately secured a channel shaped member 13 each having spaced perforated lugs 14 and 15 integrally depending from a bottom inclined wall 16 thereof.

Associated with each channel member 13 is a truck or yoke 17 each comprising spaced upstanding perforated lugs 18 and 19 adapted to be straddled by corresponding lugs of a companion channel member 13, the aligned perforations of the spaced depending lugs of a channel and the aligned perforations of the spaced lugs of a companion yoke being in registration and cooperate to receive a fulcrum rod 20 on which is seated a resilient or rubber block 21.

Each yoke is swingably mounted on a companion fulcrum rod 20 and the tension exerted by an associated resilient block 21, imparts a downwardly directed force thereon, and consequently the walls of an annular groove 22 of fulcrum rod 20 interlock and straddle the walls of the perforations 23 of depending lug 15. Hence longitudinal displacement of each fulcrum rod 20 is prevented.

The yoke 17 associated with each of the channel members 13 is provided with a transversely disposed shaft supporting hollow knuckle 24 including spaced longitudinally arranged channels or slots 25 adapted to removably receive spaced arms 26 of a resilient wire swingable shaft locking 30 loop generally denoted 27.

Spaced arms 26 of each loop terminate in upstanding terminals 28 projecting through spaced openings 29, and are disposed against a companion resilient block 21. At the other end of 35 each loop the arms 26 are bent upwardly but are interconnected by a horizontally disposed portion or lip 30.

Rotatably relative to each fulcrum rod 20 is a U shaped manipulatable locking member 31 having spaced wings 32 interconnected by a common wall 33 rotatably and eccentrically sustained on an annular shoulder 34 of a pin 35 force fitted into bore 36 of rod 20.

Spaced slots 25 divide each knuckle of the latter into three sections or ears 37, 38 and 39. Ears 37 and 39 may be considered as the outer ears and ear 38 may be termed as the intermediate ear, an outer and intermediate ear cooperating to receive a stub shaft 40 on which a wheel 41 is 50 rotatably supported. Each stub shaft 40 is provided with an annular groove or reduced portion 42 and an annular shoulder 40', limiting insertion of shaft 40 into the bearing formed by the spaced ears of a respective knuckle.

Spaced arms 26 of each locking loop 27 are disposed and guided in spaced slots 25 of an associated knuckle 24 and cooperate with aligned slots 42 of the spaced stub shafts 40 after the 5 latter are inserted in a knuckle.

If therefore manipulator 31 is rotated the sides of spaced reentrant notches 43 in spaced wings 32 straddle closed end 30 of a respective loop and the spaced wings 32 cam or displace the loop, 10 permitting arms 26 of the latter to hinge or move downwardly and enter grooves 42 of the stub shafts 40 to prevent lateral displacement of the latter. In other words, if the manipulator 32 is rotated in one direction, loop 27 hinges down- 15 wardly against the resistance of its resilient block 21, permitting the arms of the loop to interlock with the spaced stub shafts and the reentrant notches 43 in the spaced wings 32 are caused to frictionally interlock with the closed end of the 20 loop 27. Hence locking means is provided to retain the sides of the loop in interlocked relation with the stub shafts carried by each knuckle.

Complementary plate section 12 is provided with an intermediate attenuated or restricted 25 portion 44 adapted to be slidably received and guided in the transversely disposed slot 45 in the front plate section 11 and the rear attenuated part 46 of the latter includes spaced depending flanges 47. Attenuated or restricted part 46 30 of plate section 11 comprises a central elongated slot 48 on each side of which is arranged a plurality of spaced circular indentations or perforations 49.

Fixedly carried by upper rear section 12 is a 35 bolt 50 having its threaded shank 52 projecting into and through elongated slot 48. Cooperating with the threaded shank 52 is an internally threaded sleeve or bushing 53 rotatably journaled in an upper clamping plate 54 of a clutch 40 broadly designated 55, which comprises loosely and pivotally interconnected plates 54 and 56 adapted to be urged apart by a helicoidal spring 56' surrounding pin 57 carried by upper plate 54. The pivotal connection (see Fig. 2A) between the 45 upper and lower clutch plates 54 and 56 comprises a depending but inverted T shaped lug 58 having laterally extending shoulders 59 supporting a rear slotted portion 60 of the lower clutch plate 56 slidably embracing a restricted 50 part 61 of lug 58.

Rotatable bushing 53 is also rotatable relative to lower clutch plate 56 provided the latter be manually moved towards upper plate 54 and against the energy of spring 56'. In such relation, octagonal lower portion 63 of bushing 53 55 is free of a correspondingly shaped opening 62 in the lower clutch plate 56 and therefore rotation of the bushing causes upper clutch clamping plate 54 to be bodily moved towards or away 60 from restricted portion 46 of the plate section 11 depending of course, upon the direction of rotation of bushing 53.

With the lower clutch plate pressed against the upper clutch plate, rotation of bushing 53 is 65 possible by rotating winged manipulator 64 fixedly carried by the bushing. Consequently upper clutch plate may be retracted from attenuated portion 46 of the front plate section 11. Hence spaced locking detents or posts 65 carried by the 70 upper clutch plate 54 may be withdrawn from aligned openings 49 in plate section 11. Therefore, if spaced posts 65 are free of openings 49, complementary sections 11 and 12 may be slidably adjusted to any desired position.

Having slidably adjusted plate sections 11 and

12, the latter may be locked in such set position by moving spaced posts 65 of the upper clutch plate to interlock with a pair of aligned perforations 49. To this end lower clutch plate 56 is moved or manually pressed towards the upper 5 clutch plate, permitting release of the lower clutch plate 56 from the octagonal portion 63 of the bushing and consequently the latter may be rotated. Thus upper clutch plate 54 moves against rear part 46 of front section 11 and spaced 10 posts 65 thereof enter aligned perforation 49, thus holding attenuated part 46 locked and clamped between restricted part 44 of the rear section and the upper clutch plate 54.

Pursuant to locking sections 11 and 12 to 15 prevent longitudinal slippage in respect to each other, lower clutch plate 56 is manually released and bushing 53 is automatically retained against rotation, that is, the octagonal opening 62 in the lower clutch plate 56 cooperates with octagonal 20 portion 63 of the bushing preventing accidental rotation of the latter and such interlocking relation is maintained by the action of spring 56'.

Provision has been made to preclude tearing, chafing or weakening of the rear fastening straps 25 67. Hence each of the upstanding lugs 68, for locating the heel of the shoe of the wearer is provided with a swingable loop shaped clip 69 each comprising arms 70 and 71 folded over each other to provide a loop having a channel threadably receiving and slidably retaining leather strap 67. Each loop is provided with rounded edges to preclude chafing of the strap when slidably moved relative to the guide clips 69 each of which has its lower portions disposed in contact 35 and swingably or pivotally fastened to a respective heel lug 68 by a suitable rivet 72.

The forward portion of plate section 11 carries a transversely disposed threaded bolt 73 having threads 74 sloping to the left and threads 49 75 sloping to the right and adjustably mounted on bolt 73 is a pair of clamping jaws generally designated 76 each of which includes an internally threaded depending ear 77 mounted on bolt 73. Each jaw is also provided with a horizontal 45 slotted arm 78 adapted to be rectilinearly displaced upon rotation of bolt 73 by reason of the guide rivets 79 carried by section 11.

Associated with each slotted arm 78 of the rectilinearly displaceable jaws 76 is a swingable 50 clamping lip 79 adapted to grip the fore part of a shoe. More particularly, each lip 79 embodies an inturned flange 80 carrying rivet 81 rotatably disposed in slot 82 of a respective arm 78, the head 83 of each rivet 81 rotatably rests on the 55 upper portion of its associated arm. It will be apparent therefore that the swingable lips 79 when a shoe is interposed therebetween, conveniently and automatically adjust themselves to the contour of the shoe.

In accordance with the invention, winged key 84 is permanently associated with rotatable bolt 73. More particularly, key 84 is swingable relative to a link 85 and the latter is swingable in respect to bolt 73. As shown in Fig. 3, key 84 is 65 in axial alignment with bolt 73. Consequently if the key be rotated, bolt 73 will be correspondingly rotated and the jaws 78 will be rectilinearly moved towards or away from each other. In the form illustrated, key 84 is locked when disposed in axial alignment with bolt 73. In this connection, link 85 which is pivotally sustained by pins 86 and 87 secured respectively to the key and bolt comprises ends 88 abutted by tumblers or cylinders 89 slidably disposed in bores 70 75

90 of the bolt 73 and key 84. The tumblers of the latter are urged against the ends of the link 85 by helicoidal springs 91, that is, springs 91 hold the tumblers of bolt 73 and the key locked against the ends of the link and hence the key and bolt 5 73 may be disposed in axial alinement or the key may be folded with respect to the link and the latter relative to the bolt so that the key may be held locked below the bolt and substantially parallel thereto as indicated in dash and 10 dot lines illustrated in Fig. 2 and in the full lines in Fig. 3A.

In the form according to Fig. 7, a slidable modified toe clamping jaw is illustrated. In this case, 15 swingable lip 79 is provided with a depending reduced portion or detent 93 rotatably sustained and received in a perforation 94 of slotted arm 78. Hence lip 79 may be pivotally displaced relative to its supporting arm 78.

20 Each of the stub shafts 40 carries as previously stated a wheel generally designated 41 which according to the invention consists of a pair of juxtaposed but similar annular members or cups 94 and 95 each of which embodies a 25 protruding or overhanging hollow hub 96 each of which defines a ball bearing annular raceway 97.

Disposed within the housing formed by adjacent hubs 96 is an annular flange 98 integral 30 with an associated stub shaft (see Figs. 4 and 7A) and on each side of this flange there is provided an annular groove 99 forming a seat or raceway for ball bearings 100, the raceways 99 on each 35 side of flange 98 being in alinement with a raceway 97 of a companion hub.

In assembling a wheel according to the invention outer cup 94 is first placed within shell or 40 rim 101 in such a fashion that its hub 96 projects through opening 102 after which several ball bearings 100 are placed in the outer raceway 97. Stub shaft 40 is now inserted within the hub so 45 that its flange 98 is against the first layer of ball bearings. Subsequently another layer of ball bearings is positioned against the inner raceway 99 on the other side of flange 98. The inner annular member or cup 95 is then placed over the inner layer of ball bearings and the annular members 94 and 95 are fixedly secured by rivets 103 to shell 101 of the wheel.

50 With the wheel according to the invention, two layers of ball bearings are provided consequently resistance to rotation of the shell of a wheel and its ball bearing housing relative to its supporting shaft is considerably reduced. Hence less effort is required in the matter of rotating the wheel. The shell of the latter and members 55 94 and 95 thereof if desired, may be of hardened steel processed in such fashion as not to be brittle or chip. It will also be appreciated that 60 with the method herein disclosed, a wheel may be assembled on its supporting stub shaft in a comparatively short time and at a relatively low cost.

In the event a ball bearing becomes fractured 65 during periods of use, the ball bearings become jammed in their raceway. Hence the wheel becomes locked to its stub shaft and consequently the wheel will drive its supporting stub shaft and the latter will be rotated relatively to its bearings or knuckle 24. With the present invention it is 70 an easy matter to replace a wheel in the event it becomes defective for one reason or another. To replace a wheel, the operator simply actuates the eccentrically mounted manipulator 31, therefore 75 by releasing locking loop 27 from grooves 42 of

the stub shafts after which the defective wheel and its stub shaft may be slidably removed from its knuckled bearing. These steps are reversed where it is desired to mount and lock a new stub shaft to the knuckled bearing.

According to the invention, the approximate distance travelled by the skater may be readily determined or ascertained as will be described later. In this connection, a forward wheel 41 of each skate is provided with an odometer or registering device broadly designated 105, comprising as illustrated three speed reducing stages common to a crown gear 106 formed in a vertically disposed annular flange 107 of the revolute substantially horizontal shell or rim 101 of wheel 41. As shown, crown gear 106 comprises seventeen grooves as 108 defining seventeen spaced teeth 109.

Integrally carried by stub shaft 40 is an eccentric or cam 110 and extending beyond the latter but concentric with the removably fixed stub shaft 40 is the cylindrical projection or extension 111. A first stage speed reducing gear 112 having concentric opening 113 is positioned or fitted over eccentric 110. Consequently gear 112 is eccentrically disposed in respect to shaft extension 111. It will be noted, however, that gear 112 has sixteen teeth whereas crown gear 106 has one tooth more and theoretically only one tooth of gear 112 is in mesh with a groove of the 30 crown gear 106 at a time. If therefore wheel 41 is rotated, crown gear 106, which is integral with the horizontal rim or shell 101 is also rotated but in respect to its fixed shaft 40. Consequently, since at least one tooth of gear 112 is in mesh with the crown gear and gear 112 is eccentrically displaced, movement of the wheel 41 through the cooperation of the fixed eccentric 110 moves gear 112 in an orbit, that is, eccentrically with respect to shaft 40 of the revolute shell 101 and ultimately gear 112 is advanced one tooth relative to crown gear 106. Hence for each revolution of the latter, gear 112 will be advanced to mesh with a successive groove of the crown gear. That is, the eccentrically mounted gear 112 makes one 40 complete orbit after many revolutions of the crown gear 106, or in other words, gear 112 is advanced one step on each complete revolution of the crown gear 106 and therefore cooperates with the latter as the wheel revolves.

Eccentrically mounted on extension 111 of shaft 40 is an eccentric ring or annular disc 114 which includes, a pin 114 disposed in driving slot 116 of gear 112, and an eccentrically disposed opening 114'. Consequently if gear 112 is advanced in step by step fashion and eccentrically, eccentric disc 114 driven by the latter will also be advanced in step by step fashion.

An intermediate or second stage speed reducing gear 117 has a concentric and relative large 60 opening 118 mounted on the eccentrically disposed driving ring or disc 114. In other words, for every revolution of the first stage speed reducing gear 112, intermediate gear 117 is advanced one step or one tooth relative to the crown 65 gear 106 with which its teeth mesh during its eccentric motion while passing through its orbit.

Intermediate gear 117 is utilized to actuate the eccentric element or disc ring 119 having an eccentrically disposed opening 120, that is, ring 119 70 has a pin 121 disposed in driving slot 122 of the intermediate gear 117 and if the latter is driven step by step, correspondingly eccentric ring 119 is actuated step by step.

Third stage speed reducing means includes a 75

gear 123 having the large concentric opening 124', the sides of the latter being driven by the eccentric companion disc 119. As the latter is eccentrically rotated, gear 123' is moved along 5 in its eccentric orbit although a portion thereof only is in mesh with the grooves of the crown gear 106 and for every revolution of intermediate gear 117, last stage gear 123 is advanced one step or tooth relative to crown gear 106 to cooperate therewith, it being noted that the spaced reducing gears 112, 117 and 123 have the same number of teeth and concentric opening 118 is larger 10 than the opening 113 of the first stage gear and opening 124' of the last stage gear is larger than opening 118 of the intermediate stage gear to fit over respectively eccentric member 114 which is larger than eccentric 110 and eccentric element 119 which is larger than eccentric member 114.

Eccentrically disposed ring gear 123 is provided 20 with a driving pin 124 positioned in a slot 125 of a dial or indicator 126 concentrically and rotatably mounted on shaft extension 111. Consequently, as the last stage speed ring gear 123 is advanced step by step during its cooperation with the crown gear, dial or member 126 will be rotatably driven in respect to fixed shaft 40 on which it is concentrically guided.

Appropriately attached to the outside face of 30 annular flange 107 of the odometer wheel 41 is a disc shaped retaining plate 127 having a window or opening 128 permitting indicia 129 of disc member 126 to be severally viewed when registered with window 128.

Within shell 101 of the odometer wheel 41, an 35 annular spacing cup 130 is interposed between flange 107 and a companion rotatable bearing member 94, and a plurality of rivets 131 fasten the annular and complementary rotatable bearing members 94 and 95, annular flange 132 of the spacing cup 130, annular flange 107 of crown gear 106, and the closure disc 127 together. It 40 will be seen therefore that the parts of the odometer construction are compactly arranged in a relatively small space within an enclosure or housing defined by annular flange 132, annular flange 107 of shell or rim 101, and the closure disc 127.

Referring more particularly to the odometer construction, the eccentrically disposed gears 112, 117 and 123 each have sixteen teeth and the crown gear of the wheel is provided with seventeen teeth. As the crown gear 106 revolves relative to shaft 40 during contact of the horizontally disposed shell or tread on a pavement or supporting surface, for example, as in the course of skating, eccentric or cam 110 displaces companion first stage gear 112 to travel its orbit, although at least one tooth thereof is in mesh with a groove of the crown gear. By this arrangement, for one revolution of the wheel, gear 112 in effect is advanced one step only. Stated in another way, if tooth 135 of first stage gear 112 be considered as an example (see Figs. 10 and 11) and it is assumed that tooth 135 is within groove 136 of crown gear 106, it follows that after one complete revolution of the shell 101, in respect of fixed shaft 40, tooth 135 would be in registration with the next successive groove 137 of the crown gear 106. On the next revolution of shell 101 or crown gear 106 and after gear 112 has travelled through a complete orbit, tooth 135 would be in mesh 60 with the next successive groove 138. It is apparent therefore that gear 112 cooperates with the horizontally disposed teeth of the annular band of teeth formed in flange 107 to define the crown gear 106. For purposes of specification eccentric 110, gear 112 and crown gear 106 may

be considered as the first stage speed reducing means and to obtain the approximate distance travelled by the skater, the indicator readings of each registering device of both skates are additively considered to obtain a sum which is divided 5 by two to obtain the mean or average approximate distance traversed by the skater.

During the actual course of skating, the skates are alternately travelling along the ground or supporting surface. Hence one odometer wheel 10 according to the invention is attached to each skate. To determine the approximate distance travelled, the operator notes the readings of the odometer wheel of both skates before the start of the skating period and at the conclusion of the 15 latter the readings of the odometer wheels are also noted. Accordingly the displacement of the indicator members of both skates may be ascertained. The total displacement of the indicator members of both skates may then be computed 20 and this total displacement is divided by two to obtain the approximate or average displacement of the indicating members of both skates. This average or mean displacement expressed numerically may be considered as the approximate linear 25 distance traversed by the skater, that is, the average displacement of the indicating members of both skates.

Of course, a more accurate determination of the approximate distance traversed by a skater may 30 also be ascertained by the present invention. In this connection, a skater notes the mean displacement of both indicating members over a statute mile or some other definite distance. Hence each skater may determine the indicator displacement 35 characteristic or skating coefficient of his or her particular stroke or style. With this skating coefficient determined for a predetermined distance, obviously other nonpredetermined distances may be computed from the total mean displacement 40 of the indicating members or dials of both skates and therefore the peculiarity present in the course of skating, namely, one skate alternately on and off the ground is taken into consideration to obtain the approximate skating distance traversed. 45

Eccentrically disposed actuating disc 114 and companion gear 117 in cooperation with crown gear 106 may be considered as the second stage of speed reducing means and eccentric or disc 119 together with gear 123 and crown gear 106 comprise the third stage speed reducing means and it follows therefore that although all parts of the odometer except the fixed eccentric 110 bodily rotate with the wheel relative to fixed shaft 40, the distance travelled by the skater may be determined or approximated from the readings on the indicator members 126 of the registering device of both the skates, which indicators may be calibrated to read in miles or fractions thereof, however, the extent of rotary displacement of the 60 indicator dial 126 as previously mentioned being controlled by the eccentrically actuated gears 112, 118 and 123 each cooperating with crown gear 106 common thereto.

In the form illustrated, three speed reducing stages of the odometer wheel are utilized to cause one revolution of the indicator 126 for every four thousands nine hundred and thirteen revolutions of its wheel shell. This may be determined by taking seventeen to the third power, seventeen being the number of teeth on the crown gear 106 and the power or exponent taken is the number of speed reducing stages employed. If, more speed reduction of the odometer wheel is desired, additional speed reducing stages may 75

be added, or alternatively, if only one or two speed reduction stages are required, the second and third stages or the last stage respectively may be eliminated as is well understood.

5 As many changes could be made in the above construction and many widely different species or structural embodiments of the invention could be devised without departing from the scope thereof, it is intended that all matter hereinbefore 10 scribed in the specification and illustrated in the accompanying drawings shall be interpreted as illustrative and not in a limiting sense.

I claim:—

1. In combination with a fixed shaft having 15 an eccentric, rotatable means mounted on said shaft and having a portion for contacting a stationary surface to rotate said rotatable means about said shaft, eccentrically displaceable means within said rotatable means and actuated by said 20 eccentric during rotation of said rotatable means to cooperate with the latter, a member within said rotatable means and adapted to carry a plurality of indicia and rotatably mounted on said shaft and driven by said eccentrically displace- 25 able means and displaceable relative to said rotatable means during rotation of the latter, and closure means bodily carried by said rotatable means for exposing portions of said member.

2. In combination with a fixed shaft having an 30 eccentric, a wheel rotatably mounted on said shaft and having a portion adapted to contact a supporting surface to rotate said wheel relative to said shaft, said wheel having a toothed portion, eccentrically displaceable means within said 35 wheel adapted to be actuated by said eccentric for cooperating with said toothed portion, a member within said wheel and adapted to carry a plurality of spaced indicia and mounted on said shaft and adapted to be displaced by said eccentrically 40 displaceable means relative to said wheel during rotation of the latter, and means secured to said wheel for exposing a portion of said member.

3. In combination with a fixed shaft having an 45 eccentric, a wheel rotatably mounted on said shaft and having a portion adapted to contact a supporting surface to rotate said wheel relative to said shaft, said wheel having a toothed portion, eccentrically displaceable means within said wheel adapted to be actuated by said eccentric for co- 50 operating with said toothed portion, a member adapted to carry indicia and disposed within said wheel and rotatably mounted on said shaft and adapted to be displaced relative to said wheel during rotation of the latter, and a closure secured 55 to said wheel and having an opening for registering a portion of said member.

4. In combination with a fixed shaft having an 60 eccentric, a wheel rotatably retained on said shaft having a substantially horizontally disposed portion for contacting a supporting surface to rotate said wheel about said shaft and having a substantially vertically arranged toothed member, a rotatable member concentrically mounted on said shaft and adapted to carry a plurality of 65 spaced indicia, means actuated by said eccentric and cooperating with said toothed member during rotation of said wheel relative to said shaft for displacing said rotatable member in respect to said revolving wheel, and means secured to 70 said toothed member for exposing a portion of said rotatable member.

5. In combination with a fixed shaft having an 75 eccentric, a wheel rotatably mounted on said shaft and having a horizontally disposed portion for contacting a supporting surface and includ-

ing an annular flange having a plurality of teeth, spaced means secured to said flange defining therewith a housing, means cooperating with said teeth and actuated by said eccentric during rotation of said wheel, and a member adapted to carry indicia and disposed within said housing and driven by said means cooperating with said teeth and displaceable in respect to said wheel during rotation of the latter, for registering a portion of said member with a portion of said housing.

6. In combination with a fixed shaft having an eccentric, a wheel rotatably mounted on said shaft including a horizontal portion for contacting a supporting surface to rotate said wheel and having an annular flange including a plurality of teeth, means secured to said flange defining therewith a housing having an opening, eccentrically displaceable means actuated by said eccentric and cooperating with said teeth during rotation of said wheel, and eccentrically displaceable means driven by said first mentioned eccentrically displaceable means and cooperating with said teeth, and a rotatable member adapted to carry spaced indicia and connected to and displaced relative to said wheel during rotation of the latter by said second mentioned eccentrically displaceable means, said rotatable member having portions thereof adapted to severally register with said opening during rotation of said wheel relative to said shaft.

7. In combination with a removably fixed shaft having an eccentric, a wheel rotatably retained thereon, said wheel having a substantially vertically disposed flange having horizontally arranged teeth, spaced means secured to said flange constituting therewith a housing having an opening, driven means comprising a gear actuated by said eccentric during rotation of said wheel and cooperating with said teeth, an eccentric member driven by said gear, a gear mounted on said eccentric member and actuated thereby to cooperate with said teeth during rotation of said wheel, and a rotatable member adapted to carry spaced indicia and actuated by said driven means and rotatively displaceable relative to said wheel during rotation of the latter in respect to said shaft, said rotatable member having portions adapted to register with said opening during rotation of said wheel.

8. In combination with a removably fixed 50 shaft having an eccentric, a wheel rotatably retained thereon, said wheel having a substantially vertically disposed flange having substantially horizontally arranged teeth, spaced means straddling said flange to define therewith a housing including an opening, a gear mounted on said eccentric and actuated thereby during rotation of said wheel to cooperate with said teeth, an eccentric member driven by said gear, a gear mounted on said eccentric member and actuated 55 thereby to cooperate with said teeth during rotation of said wheel, an eccentric element driven by said last mentioned gear, a gear mounted on said eccentric element and actuated thereby to cooperate with said teeth during rotation of said wheel, a rotatable member adapted to carry spaced indicia and driven by said last mentioned gear and adapted to be displaced relative to said wheel during rotation of the latter and having portions thereof adapted to severally register with said opening during rotation of said wheel relative to said shaft.

9. In combination with a fixed shaft having an eccentric and an extension, a wheel rotatably retained on said shaft, said wheel having a substan- 75

5 tially horizontally disposed portion for contacting a supporting surface to rotate said wheel relative to said shaft, said wheel having a gear including substantially horizontally disposed teeth, 5 means cooperating with said teeth adapted to be actuated by said eccentric and eccentrically disposed relative to said extension, a member adapted to carry spaced indicia and rotatably mounted on said extension and driven by said means operating with said teeth and adapted to be displaced relative to said wheel during rotation of the latter, and means secured to and bodily rotatable with said gear for exposing a portion of said driven and rotatable member.

10 15. In combination with a fixed shaft having an eccentric and a concentric extension, a wheel rotatably retained on said shaft, said wheel having a substantially horizontally disposed portion for contacting a supporting surface to rotate said wheel in respect to said shaft, said wheel having a flange including an annular band of spaced teeth, spaced means secured to said flange and defining therewith a housing having an opening, eccentrically actuated means comprising a gear actuated by said eccentric and cooperating with said teeth, an eccentric member mounted on said extension and driven by said gear, a gear mounted on said eccentric member and cooperating with said teeth, an eccentric element mounted on said extension and driven by said last mentioned gear, a gear mounted on said eccentric element and cooperating with said teeth, and a rotatable member adapted to carry a plurality of spaced indicia and driven by said last mentioned gear and having portions adapted to severally register with opening during rotation of said wheel relative to said shaft.

20 25 30 35 40 45 50 55 60 65 70 75 11. In combination with a fixed shaft having an eccentric and a concentric extension, a wheel rotatably retained on said shaft, said wheel having a substantially horizontally disposed portion for contacting a supporting surface to rotate said wheel in respect to said shaft, said wheel including a flange having an annular band of spaced teeth, spaced means secured to said flange and defining therewith a housing having an opening, and eccentrically actuated means comprising a gear actuated by said eccentric and cooperating with said teeth, an eccentric member mounted on said extension and driven by said gear and having a size larger than said eccentric, a gear mounted on said eccentric member for cooperating with said teeth, an eccentric element mounted on said extension and driven by said last mentioned gear and having a size larger than said eccentric member, a gear mounted on said eccentric element and adapted to cooperate with said teeth, and a member rotatably mounted on said extension and driven by said last mentioned gear and adapted to carry a plurality of spaced indicia and having portions adapted to register with said opening during rotation of said wheel relative to said shaft.

12. In combination with a fixed shaft having an eccentric and a concentric extension, a wheel rotatably retained on said shaft, said wheel having a substantially horizontally disposed portion for contacting a supporting surface to rotate said wheel in respect to said shaft, said wheel having a flange including an annular band of spaced teeth, spaced means secured to said flange and defining therewith a housing having an opening, eccentrically actuated means comprising a gear actuated by said eccentric and cooperating with said teeth, an eccentric member mounted on said

extension and driven by said gear, a gear mounted on said eccentric member and cooperating with said teeth, an eccentric element mounted on said extension and driven by said last mentioned gear, a gear mounted on said eccentric element and 5 cooperating with said teeth, and a member driven by said last mentioned gear and adapted to carry a plurality of indicia and having a portion adapted to register with said opening during rotation of said wheel relative to said shaft, the first, second and third mentioned gears having the same number of teeth, and said band comprises at least the number of teeth of either of said mentioned gears plus one tooth, and said band of teeth being common to all of said mentioned gears.

10 15 20 25 30 35 40 45 50 55 60 65 70 75 16. As a new article of manufacture, a shaft having an eccentric and a concentric portion overhanging said eccentric, a wheel rotatable relative to said shaft and comprising a crown gear, a spur gear disposed in an extension of the plane of said eccentric and having a plurality of teeth severally cooperating with the teeth of said crown gear and having a concentric opening closely but movably surrounding said eccentric and adapted to be eccentrically displaced thereby during rotation of said wheel, eccentrically displaceable means actuated by said spur gear, and a member rotatable relative thereto a terminal of said concentric portion and actuated by said eccentrically displaceable means and displaceable relative to said wheel during rotation thereof.

17. As a new article of manufacture and in combination, a nonrotatable shaft having an eccentric integral therewith and a concentric portion overhanging said eccentric and integral therewith, a wheel rotatable relative to said shaft, a crown gear bodily rotatable with said wheel, and a spur gear substantially in alinement with said eccentric having a plurality of teeth severally cooperating with the teeth of said crown gear and having a concentric opening closely but movably surrounding said eccentric and adapted to be eccentrically displaced thereby during rotation of said wheel, eccentrically displaceable means adapted to cooperate with said crown gear and actuated by said spur gear, and a member rotatable relative to said concentric portion and actuated by said eccentrically displaceable means and displaceable relative to said wheel during rotation thereof about said shaft.

18. As a new article of manufacture and in combination, a nonrotatable shaft having an eccentric and a concentric portion overhanging said eccentric, a member rotatable relative to said shaft, a crown gear bodily rotatable with said member, a spur gear having a plurality of teeth severally cooperating with the teeth of said crown gear and having a concentric opening closely but movably surrounding said eccentric and adapted to be eccentrically displaced thereby relative to said shaft during rotation of said member, disc means having an eccentric opening surrounding said concentric portion, a spur gear having a concentric opening closely but movably surrounding said disc means, and means for displacing said disc means during displacement of said first mentioned spur gear, said disc means during displacement thereof during rotation of said member causing said second mentioned spur gear to be eccentrically displaced to permit the teeth thereof to severally cooperate with the teeth of said crown gear.

19. As a new article of manufacture and in combination, a nonrotatable shaft having an eccentric and a concentric portion overhanging said eccentric, a member adapted to contact a

fixed surface to rotate relative to said shaft, a crown gear bodily rotatable with said member, a spur gear disposed substantially in alignment with said eccentric and having a plurality of teeth severally cooperating with the teeth of said crown gear and having a concentric opening closely but movably surrounding said eccentric and adapted to be eccentrically displaced thereby relative to said shaft during rotation of said member, disc means having an eccentric opening closely but movably surrounding said concentric portion, a spur gear having teeth severally cooperating with the teeth of said crown gear and having a concentric opening closely but movably surrounding said disc means and disposed substantially in alignment with the latter, and means for displacing said disc means during displacement of said first mentioned spur gear, said disc means during displacement thereof during rotation of said member causing said second mentioned spur gear to be eccentrically displaced to permit the teeth thereof to severally cooperate with the teeth of said crown gear.

17. The article of manufacture according to claim 16 in which the disc means is larger than said eccentric, and the concentric opening of said second mentioned spur gear is larger than the concentric opening of the first mentioned spur gear.

18. The article of manufacture according to claim 16 in which the disc means is larger than said eccentric, and the concentric opening of said second mentioned spur gear is larger than the concentric opening of the first mentioned spur gear and wherein the teeth of the first and second mentioned spur gears have the same number of teeth and said crown gear has one tooth more than either of said spur gears.

19. As a new article of manufacture and in combination, a shaft having an eccentric and a concentrically arranged portion extending laterally of said eccentric and integral therewith, a wheel adapted to contact a fixed surface to rotate relative to said shaft, means constituting crown gear means bodily rotatable with said wheel, a spur gear disposed substantially in alignment with said eccentric and having a plurality of teeth severally cooperating with the teeth of said crown gear means and having a concentric opening including a wall closely but movably surrounding said eccentric and adapted to be eccentrically displaced thereby relative to said shaft during rotation of said wheel, disc means having an eccentric opening including a wall closely but movably surrounding said concentrically arranged portion, a spur gear having teeth severally cooperating with the teeth of said crown gear means and having a concentric opening including a wall closely but movably surrounding said disc means and disposed substantially in alignment with the latter, means for displacing said disc means during displacement of said first mentioned spur gear, said disc means during displacement thereof during rotation of said wheel causing said second mentioned spur gear to be eccentrically displaced to permit the teeth thereof to severally cooperate with the teeth of said crown gear, disc means having an eccentric opening closely but movably surrounding said concentric portion and having means driven by said second mentioned spur gear, a spur gear disposed substantially in alignment with said second mentioned disc means and having a concentric opening closely but movably surrounding said second mentioned disc means and actuated by the latter to severally cooperate with the teeth of said crown gear during rotation of said wheel, a member rotatably mounted adjacent a terminal of said concentric portion, and means operatively connecting said third mentioned spur gear and member for displacing the latter relative to said wheel during rotation of the latter.

22. An article of manufacture and in combination, a non-rotatable shaft having an eccentric and a concentric portion overhanging said eccentric, a wheel adapted to contact a fixed surface to rotate relative to said shaft, a crown gear bodily rotatable with said wheel, a spur gear disposed substantially in alignment with said eccentric and having a plurality of teeth severally cooperating with the teeth of said crown gear and having a concentric opening closely but movably surrounding said eccentric and adapted to be eccentrically displaced thereby relative to said shaft during rotation of said wheel, disc means having an eccentric opening closely but movably surrounding said concentric portion, a driving connection between said spur gear and disc means, a spur gear having teeth severally cooperating with the teeth of said crown gear and having a concentric opening closely but movably surrounding said disc means and disposed substantially in alignment with the latter, means for displacing said disc means during displacement of said first mentioned spur gear, said disc means during displacement thereof during rotation of said wheel causing said second mentioned spur gear to be eccentrically displaced to permit the teeth thereof to severally cooperate with the teeth of said crown gear, a member rotatably mounted adjacent a terminal of said concentric portion, and eccentrically displaceable means operatively interconnecting said second mentioned spur gear and said member for displacing the latter during rotation of said wheel.

23. As a new article of manufacture and in combination, a non-rotatable shaft having an eccentric and a concentric portion overhanging said eccentric, a wheel adapted to contact a fixed surface to rotate relative to said shaft, a crown gear bodily rotatable with said wheel, a spur gear disposed substantially in alignment with said eccentric and having a plurality of teeth severally cooperating with the teeth of said crown gear and having a concentric opening closely but movably surrounding said eccentric and adapted to be eccentrically displaced thereby relative to said shaft during rotation of said wheel, disc means having an eccentric opening closely but movably surrounding said concentric portion, a driving connection between said disc means and spur gear, a spur gear having teeth severally cooperating with the teeth of said crown gear and having a concentric opening closely but movably surrounding said disc means and disposed substantially in alignment with the latter, means for displacing said disc means during displacement of said first mentioned spur gear, said disc means during displacement thereof during rotation of said wheel causing said second mentioned spur gear to be eccentrically displaced to permit the teeth thereof to severally cooperate with the teeth of said crown gear, disc means having an eccentric opening closely but movably surrounding said concentric portion and having means driven by said second mentioned spur gear, a spur gear disposed substantially in alignment with said second mentioned disc means and having a concentric opening closely but movably surrounding said second mentioned disc means and actuated by the latter to severally cooperate with the teeth of said crown gear during rotation of said wheel, a member rotatably mounted adjacent a terminal of said concentric portion, and means operatively connecting said third mentioned spur gear and member for displacing the latter relative to said wheel during rotation of the latter.

22. The article of manufacture according to 75

claim 21 wherein, the eccentric is smaller than said first mentioned disc means and the latter is smaller than the second mentioned disc means, and wherein the concentric opening of the third mentioned spur gear is larger than the concentric opening of the second mentioned spur gear which in turn is larger than the concentric opening of the first mentioned spur gear.

23. The article of manufacture according to
10 claim 21 wherein the concentric opening of the

first mentioned spur gear closely but movably surrounds the periphery of the eccentric and the concentric opening of the second mentioned spur gear closely but movably surrounds the periphery of the first mentioned disc means and the concentric opening of the third mentioned spur gear closely but movably surrounds the periphery of the second mentioned disc means.

SAMUEL SEGAL. 10
